UNITED STATES PATENT OFFICE

WILLIAM B. PALMER, OF CONEJO, CALIFORNIA.

CHECK-BOOK.

1,307,143.

Specification of Letters Patent. Patented June 17, 1919.

Application filed April 18, 1917. Serial No. 162,870.

To all whom it may concern:

Be it known that I, WILLIAM B. PALMER, a citizen of the United States, residing at Conejo, in the county of Fresno and State 5 of California, have invented certain new and useful Improvements in Check-Books, of which the following is a specification.

This invention relates to improvements in check books, more particularly although not 10 exclusively to what are known as pocket check books, such as are commonly carried on the person of the user. The principal object of the invention is to provide a check book which shall embody in and as a part 15 of its physical structure a handy and convenient means for delimiting each check therein and preventing its fraudulent raising to any amount substantially greater than that for which it is drawn.

20 Check limiting machines and devices of various sorts are, of course, in quite general use; but, so far as I am aware, these are for the most part entirely separate and distinct from the check book itself, and, where sufficiently small and light to be carried on the 25 person of the user, are easily lost, mislaid or forgotten. Some of these devices are detachably mounted on the cover of the check book so as to be removable for use with a new book when the old book is exhausted; but even such devices are liable to become 30 separated from the book and lost. One characteristic of my present invention is the fixed and permanent association and connection 35 of the check limiting means with the check book itself, and a further object of the invention is to provide, permanently bound in or otherwise connected to the check book, a check limiting device of such simple and 40 inexpensive structure that banks can readily afford to give them away to their customers.

45 My invention, its manner of use, and the merits and advantages inherent therein will be readily appreciated and understood from the following detailed description taken in connection with the accompanying drawings forming a part of this specification, wherein—

50 Figure 1 is a perspective view of a foldable pocket check book having my present invention embodied therein;

55 Fig. 2 is a cross section on the line 2—2 of Fig. 1 illustrating one simple means of permanently binding the check limiting device to the stub of the book;

Fig. 3 is a plan view illustrating the man-

ner of marginally notching a check to delimit the same;

Fig. 4 is a fragmentary view showing a portion of the check after it has been delimitated.

Referring to the drawings, 5 designates the cover, 6 the stubs, 7 the checks, and 8 the flap of a common type of pocket check book now in general use which is foldable 65 substantially midway of its length.

Referring to the checks themselves, it will be observed that each check is provided along its four margins with rows 9 of numerals in multiples of 5 and 10 having a 70 range of from \$1 to \$1000. In the lower left hand corner of the check is a printed notice 10 indicating that the check is not good for more than the smallest amount notched out on the margin. The checks are 75 detachably connected to the stubs by the usual perforated lines 11.

12 designates a thin plate, preferably of sheet steel, from which is punched a raised V-shaped tongue 13. On either side of the 80 tongue 13 are a pair of upset lugs 14 forming stops for the edge of the check in the manner clearly shown in Fig. 3, when the edge of the check is inserted beneath the tongue 13. The opposite edges of the plate 85 12 are preferably notched as shown at 15, and the plate is permanently attached to and bound in the stub of the book by a wire clip or clamp 16 engaging the upper surface and notches of the plate and extending through 90 the stub and cover, the ends 16' of the clip being bent beneath the cover, as clearly shown in Fig. 2.

In the use of the invention, when a check 95 has been drawn, it is torn from its stub and one margin thereof is then inserted beneath the tongue 13 and against the stops 14 so that the tongue overlies the number indicating the amount for which the check is drawn, or the next largest even number in 100 excess of the amount for which the check is drawn. With the thumb of one hand pressing on the tongue 13, the check is then drawn upwardly and rearwardly by a quick movement of the other hand, thus providing the 105 marginal notch 17 shown in Fig. 4, this notch indicating that the check is not good for an amount greater than that which has been notched out.

The entire delimiting means, including 110 the notching device permanently bound in the stub and the marginal numbering of the

checks involves such a trifling additional cost in the manufacture of the check book that banks can readily afford to furnish them to their customers. It will readily be seen that so long as the book lasts it is impossible to dissociate the limiting means from the book itself, which I consider a great advantage over check limiting devices which are entirely separate and easily liable to be lost or mislaid.

Without limiting myself to the precise details shown and described, I claim:

1. The combination with a check-book having a stub portion, of a check-notching device comprising a plate located on the top of said stub portion and having an integral tongue raised above the plane of the plate, and means for fixedly securing said plate to said stub portion.

2. The combination with a check-book 20 having a stub portion, of a check notching device comprising a plate located on the top of said stub portion and having an integral tongue and stop lugs on either side of said tongue respectively, both said tongue and 25 stop lugs being raised above the plane of the plate and means for fixedly securing said plate to said stub portion.

3. The combination with a check-book including a plurality of checks and stubs 30 therefor permanently bound in said book, of a check notching device comprising a plate having an integral raised tongue and stop lugs on either side of said tongue respectively, and means for fixedly securing 35 said plate to, and in a position overlying, the stubs of the check-book.

WILLIAM B. PALMER.
